UNITED STATES PATENT OFFICE.

GEORGE GOULD GOING, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,326,657.

Specification of Letters Patent. Patented Dec. 30, 1919.

Application filed June 1, 1917. Serial No. 172,172.

To all whom it may concern:

Be it known that I, GEORGE GOULD GOING, a citizen of the United States, residing at Middletown, in the county of Middlesex 5 and State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and more particularly to improvements in case-shifting mechanisms thereof 15 employed to alter the relation between the type bars and the platen.

One of the objects of the invention is to provide simple and efficient means of the character mentioned capable of easy operation to effect accurate positioning of the shiftable part.

Other objects will be in part obvious and in part noted hereinafter in connection with the following description of the accompanying drawing, which illustrates a typical embodiment of the invention, and in which—

Figure 1 is a fragmentary plan view showing the improved case-shifting mechanism;

Fig. 2 is a sectional side view when the parts are in one position; and

Figs. 3 and 4 are fragmentary side views showing the movable parts in opposite extreme positions.

The invention as illustrated is designed for incorporation in a noiseless typewriter, but is adapted for application to various styles of machines. The moving parts of the mechanism shown are mounted upon a

typewriter frame comprising side walls 1, a rear cross piece 2 and a front cross piece 3. Above the machine and at the rear thereof is arranged a traveling carriage mounted for letter-space and vertical case-shifting

movement upon a carriage rail 4 (Fig. 2). The letter-space movement of the carriage is governed by suitable escapement mechanism of any of the well-known types. The carriage rail 4 extends transversely and is

supported adjacent its ends by a pair of vertical shift rods 5 trunnioned at their lower ends in parallel arms 6 fixed to rotate with a transverse rock shaft 7, in turn trunnioned between the rigid side walls of the

machine. The upper ends of the shift rods 5 are also suitably connected with a part of the machine in such a manner that rocking movement of the arms 6 effects vertical movement of the carriage rail 4, preferably, however, without longitudinal displacement 60 of the latter; that is, the construction is designed to effect vertical case-shifting from an intermediate to an upper or lower limit in a single vertical plane. The construction referred to may be such as that shown 65 in Patent No. 1,155,634, issued October 5, 1915 to N. H. Anderson.

Coiled counter-balancing springs 8 are preferably positioned about the rock shaft 7 to react between the latter and a stationary part, such as the cross piece 2, and are provided with tension adjusting means 9 by which the force of the springs is utilized to counterbalance the weight of the carriage parts and normally to urge the carriage to 75 medial position. Case-shifting movement of the carriage rail 4 is imparted by a force applied directly to a lateral stud 10 fixed suitably, and preferably adjustably, on the left vertical shift rod 5. To reduce friction, the stud 10 may be provided with a terminal roller 11 which works in a cam path 12 of a rocking lever plate 13. The plate 13 is also provided with a depending arm 14 by which the plate is pivoted to 85 stationary lugs on the cross piece 2. The cam slot 12 is designed, in the configuration shown, to provide a central dwell 15, a terminal dwell 16 and a terminal dwell 17 at the opposite end. The dwells mentioned 90 are connected by inclined cam walls so that, as the lever plate 13 is rocked about its axis from one extreme position to the other, the stud 10 is raised or lowered from one extreme position, through intermediate, to 95 the other extreme position. In each position mentioned, however, the stud roller 11 rests in a dwell of the cam slot whereby the carriage rail is accurately held against vibration and whereby the gravity or spring 100 tendency of the carriage to return from either extreme position may be easily resisted by the stable relationship between the rocker plate 13 and the stud 10. From the foregoing description it will be understood, of course, that vertical movement of stud 10 carries the shift rods 5 correspondingly, and thereby elevates or lowers the

carriage rail and its supported parts to bring the platen in coactive relation with the desired type set.

For rocking actuation of the cam plate 13 there are provided shift key levers 18 and 19 terminating at their forward ends, respectively, in a figure key 20 and a capital key 21. The lever 18 is medially pivoted on a stud 22 fixed to the left side wall 1 of the machine, frame, and thence extends downward and rearward to terminate in an offset stud 23 positioned to coact with the front lower edge 24 of the cam plate 13. The lever 19 is medially fixed to a rock shaft 25 truncated between the side walls 1 of the machine frame and from thence extends rearward to terminate in an offset lug 26 positioned to coact with the lower rear edge 27 of the cam plate 13. The levers 18 and 19 are normally urged to intermediate position, and may be conveniently so urged by a single coil spring 28 extended between a lug 29 on lever 18 and an aperture 30 on lever 19.

25 The parts described, by their construction and arrangement, coöperatively function as follows: Depression of the figure key 20 raises the stud 23 so that the latter wipes over the edge 24 of cam plate 13 and rocks the latter rearward, whereby the cam slot 12 carries stud 10 downward and thus depresses the carriage and platen to the lowest position in which the predetermined sets of type may operate to effect printing.

30 Rearward movement of the cam plate 13 during the operation described is permitted with respect to the stud 26 on the lever 19, due to the cut-away edge 30' of the cam plate. The lower case shift position of the 40 parts is as shown in Fig. 4.

Similarly, depression of the capital key 21 from the intermediate position of Fig. 2 causes stud 26 to ride over cam edge 27 of plate 13 and rock the latter forwardly, 45 whereby the cam slot 12 effects elevation of stud 10 and the carriage movable therewith. Such forward movement of the plate 13 is permitted with respect to stud 23 on lever 18 by reason of the cut-away edge 31 of the 50 plate.

Release of the shift key when the carriage is in an extreme position permits counter-balancing springs 8 to exert their force through the carriage support to effect its 55 automatic and immediate return to intermediate position. For convenience in operation there is also preferably provided an additional capital key lever 19' arranged on the opposite side of the machine and fixed 60 to the rock shaft 25, so that capital case

shifting can be effected at either side of the key lever bank. The shift keys 18 and 19 are also preferably provided with locking keys 20' and 21' having latched lower extremities adapted to engage beneath the 65 edges of a locking plate 32 attached to the wall of the machine.

While, in the construction shown in the drawing and in the foregoing description, reference is made to a shifttable carriage, it is 70 to be understood that the invention is susceptible of embodiment in other styles of machines where, for example, the type bars are shifted.

As many changes could be made in the 75 above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention, which, as a matter of language, 80 might be said to fall therebetween.

Having described my invention, what I claim as new and desire to secure by Letters Patent is:

1. In a typewriting machine, in combination, a shifttable part having three case positions, a pair of shift key levers therefor selectively operable to move said part from intermediate position to an extreme position, and an operative connection between said levers and said part including a pivoted member having a cam slot within which said part works and having portions coöperable with said levers to limit actuating movement of the latter.

2. In a typewriting machine, in combination, a vertically shifttable carriage having opposite extreme and intermediate case positions, shifting means therefor including a rocking member having a cam to control movement of said carriage, and shift key levers normally out of contact with but selectively movable to engage said member on opposite sides of the axis of the latter.

In testimony whereof I affix my signature, in the presence of two witnesses.

GEORGE GOULD GOING.
